US0D1060446S

(12) **United States Design Patent** (10) **Patent No.:** **US D1,060,446 S**
(45) **Date of Patent:** **** Feb. 4, 2025**

(54) **DIAMOND DRILL BIT**

(71) Applicant: **Yangzhou Jiedeng Trading Co., LTD**,
Gaoyou (CN)

(72) Inventor: **Xilan Chen**, Gaoyou (CN)

(73) Assignee: **Yangzhou Jiedeng Trading Co., LTD**,
Gaoyou (CN)

(**) Term: **15 Years**

(21) Appl. No.: **29/879,415**

(22) Filed: **Jul. 7, 2023**

(51) LOC (15) Cl. **15-09**

(52) U.S. Cl.

USPC **D15/139**
